UNITED STATES PATENT OFFICE.

BENJAMIN R. JOLLY, OF RALEIGH, NORTH CAROLINA.

DESIGN FOR A BADGE, CHARM, STICK-PIN, FLAG, SIGN, FOB, OR EMBLEM.

51,679.

Specification for Design.

Patented Jan. 8, 1918.

Application filed October 11, 1917. Serial No. 196,077. Term of patent 7 years.

To all whom it may concern:

Be it known that I, BENJAMIN R. JOLLY, a citizen of the United States, residing at Raleigh, in the county of Wake and State of North Carolina, have invented a new, original, and ornamental Design for a Badge, Charm, Stick-Pin, Flag, Sign, Fob, or Emblem, of which the following is a specification, reference being had to the accompanying drawing, forming part thereof.

The figure is a plan view of an emblem showing my new design.

I claim:

The ornamental design for a badge, charm, stick pin, flag, sign, fob, or emblem, as shown.

BENJAMIN R. JOLLY.
